UNITED STATES PATENT OFFICE.

MYRON M. BUCK, OF ST. LOUIS, MISSOURI.

DESIGN FOR A HEAD-LIGHT.

SPECIFICATION forming part of Design No. 18,719, dated November 6, 1888.

Application filed September 3, 1888. Serial No. 284,516. Term of patent 14 years.

To all whom it may concern:

Be it known that I, MYRON M. BUCK, of the city of St. Louis, in the State of Missouri, and a citizen of the United States, have invented and produced a new and original Design for Locomotive Head-Lights, of which the following is a specification, reference being had to the accompanying drawings, forming part thereof.

10 Figure I is a perspective view of a head-light, showing my design. Fig. II is a side elevation of same.

In the said drawings, 1 represents the body of the head-light, and 2 the front rim which surrounds the opening before the parabola 3. The body 1 is provided at its top with a slightly-raised surface, 4, whose front and sides slant upward toward a common point, but whose back is perpendicular and forms a straight outline with the back of the body and also with the back of the box 5, resting upon the surface 4, as plainly shown in Fig. II. The sides of the box 5 are provided with the signal-num-

bers 6, which sides are preferably perpendicular, and are surmounted by the inwardly and upwardly curving roof or extension 7, having the chimney 8 protruding therethrough at its summit. The leading feature of my design, however, consists of the head-light having the straight outline at the back, formed by the body and the number-box, while I consider the other features mere auxiliaries to enhance the beauty of a head-light thus made.

What I claim is—

A design for locomotive head-lights herein shown and described, the same comprising the body 1 and number-box 5, the back of the latter being in line with the back of the former, as set forth.

In witness whereof I have hereunto set my hand in the presence of two witnesses.

MYRON M. BUCK.
